UNITED STATES PATENT OFFICE.

THOMAS R. GOTH, OF SAN FRANCISCO, CALIFORNIA.

DREDGING APPARATUS.

No. 868,774.

Specification of Letters Patent.

Patented Oct. 22, 1907.

Application filed February 5, 1906. Serial No. 299,599.

To all whom it may concern:

Be it known that I, THOMAS R. GOTH, a citizen of the United States, residing at San Francisco, in the county of San Francisco and State of California, have 5 invented certain new and useful Improvements in Dredging Apparatus, of which the following is a specification.

This invention relates to the art of dredging and more particularly to dredging for gold or other valuable 10 material wherever found. I employ a rotary digger as an excavator, but in distinction from the ordinary so-called suction dredgers. I use a powerful stream of water having an injective action for delivering the material through and from the dredging tube or pipe. I 15 use a rotary snail-shaped cutter which excavates the material in combination with a hydraulic giant which elevates such material, and forces it through a discharge pipe to proper washing and separating apparatus. There are many advantages pertaining to my 20 construction, many of which are hereinafter stated; and these advantages result whether my dredger be compared with the ordinary so-called suction or hydraulic dredge, or with the chain bucket dredge commonly used in dredging for gold.

25 An embodiment of my invention will be found in the accompanying drawings in connection with which this description should be read, and in which

Figure 1 is a sectional elevation of the entire machine, Fig. 2 is a plan view with certain parts in horizontal section, Fig. 3 is a plan view of the digging head, Fig. 4 shows a modified arrangement for driving a rotary digging head with a stationary inlet pipe.

At 1 is shown a suitable hull or scow for sustaining the dredging and washing machinery. At 2 is a revolving pipe supported on rollers 3 journaled in the truss frame or ladder 4, which projects from the bow of the hull, said bow being open in pontoon fashion, so as to permit the convenient raising and lowering of the rotary pipe. Said pipe is rotated by gears 5 and 6 35 which are connected into a system of gearing to be hereinafter described. The truss frame is supported from above in any suitable manner, and has proper tackle connected to the hoist or windlass 7.

On the lower end of the rotary pipe is the excavating 45 head 8. This head is secured rigidly to the pipe 2 and revolves with it. This head is of snail shape and has a single projecting cutter 9, and a single interior curved vane 11, which as the material is cut forces it to the center of the digging head and up the rotary pipe. 50 The rotary pipe, at its upper end has an air tight bearing 12, in the elbow 13, and in order that the excavator can be adjusted to dig at any depth, such elbow is formed in two parts with a packed joint 14 between them. The stationary part 13^a of the elbow is connected to a discharge pipe 15.

The material is forced into and through the elbow

and discharge pipe by the powerful hydraulic giant 16 within the branch pipe or casing 17 which has a bearing upon it, and supplied by the centrifugal pump 18. The rotary pipe, the movable part of the elbow and the 60 branch pipe 17 form practically a T-shaped adjustable hydraulic mechanism, all of which swing together as upon a hinge joint or trunnions when the digger is adjusted to cut at any angle of depth or of elevation.

A system of gearing for driving all parts of the machinery is shown in the drawing and although susceptible of modification, it is what I prefer to use, because in a simple way, it permits the adjustments required in effective dredging without becoming deranged. I have shown as the primary power a motor 70 19, from which shaft a belt 20 drives a shaft 21. A belt 22 from shaft 21 drives the centrifugal pump 18. Another belt 23 from shaft 21 drives the shaft 24 which carries the miter gear 25. Loose on the pipe or casing which surrounds the hydraulic giant is an intermediate gear 26 engaging with miter gear 25 and also with miter gear 27 on the shaft 28 which carries the spur gear 5 which as previously stated transmits the rotary motion to the pipe 2. The intermediate gear being 75 loose on the pipe casing transmits power freely, no matter what the adjustment of said casing, elbow, and rotary pipe may be.

The material forced into and through the discharge pipe 15 is delivered into a revolving drum 29 having numerous perforations as shown. The drum is mounted on a shaft 31 and is driven by a sprocket connection from the shaft 21. Coarse material too large to pass the perforations in the drum is discharged upon the chute 32. Fine material, that is sand and small gravel in which all the gold is contained pass through the perforations upon the rifled surface 33. There may be a series of these rifled surfaces if desired, and they may be provided with any of the well known gold saving means such as amalgamated plates. The water which passes through the perforations in the drum is 90 used upon the rifles for washing and separating purposes.

The sand and water on leaving the rifles discharge into a sump 34 where the sand settles to the bottom and is removed and discharged by the chain of buckets 100 35 which is driven by bevel gearing 36 from the drum shaft and sprocket gearing 30, as best shown in Fig. 2. The water collects naturally in the sump and overflows at its edge.

At 37 is a gate valve which can be used to close the 105 discharge pipe, so that if the rotary pipe should become clogged, all the power of the giant can be directed backwardly to wash it clear.

This machine should be clearly distinguished from the ordinary so-called suction or hydraulic dredge. 110 The latter is not successful in raising coarse gold, because it depends entirely upon the action of the cen-

trifugal suction pump to raise all the material excavated by the cutter. Gold having about eight times the specific gravity of the material with which it is associated, the pump suction naturally draws the sand and gravel from underneath, allowing the gold itself to settle away from the entrance and be lost.

With the present invention the rotary shovel or head scoops up gold, sand, gravel rock, etc., as it revolves and deposits all such material mechanically within the 10 rotary pipe, in which it is easily elevated by the hydraulic giant, and is afterward thoroughly washed and separated. The point of the shovel or digger is preferably made triangular so that any rock too large to be received by the single opening is forced to the edge 15 and out of the way. Its motion through the ground also loosens any adherent particles of gold which are then scooped up, or sucked up by the action of the hydraulic giant.

It will be noted that the coarse material is delivered 20 from the screen or drum at the rear and falls by gravity to the bottom of the hole in which the dredger is at work, while the sand and earth being elevated to a higher point falls upon and above such rock. This requires no more power and leaves the country in condition 25 for agricultural operation again, while the bucket dredger leaves the country around it a barren rock pile.

The material is more thoroughly broken up in its passage by the giant elevator, than can possibly be the case with a chain of buckets. This results in easier, quicker 30 and better washing and separation.

As the inlet pipe revolves, the material cannot settle 35 in the bottom and clog the opening, but is continually rolled over and over and ground up and separated by its own impact and that of the large stones or boulders which form a portion of it.

Other advantages might be enumerated, but it is believed that in view of the foregoing description they will be apparent to those skilled in the art.

I do not limit myself to the precise features of construction hereinbefore described and shown in the accompanying drawings, as I desire to avail myself of such modifications and equivalents as fall properly within the spirit of my invention. For instance as shown in Fig. 4 the digging head might be connected to a stationary suction pipe and rotated by a sprocket chain, or in any equivalent way; but I prefer to use the rotary suction pipe.

Having thus described my invention what I claim as new and desire to secure by Letters Patent, is:—

- 50 1. In a dredger, a rotary snail-shell shaped digger or excavator.
2. In a dredger, a rotary snail-shell shaped digger or excavator having a single projecting cutting edge, and a single inlet opening.
- 55 3. In a dredger, a rotary snail-shell shaped digger in combination with a rotary pipe to which said digger is rigidly secured.
4. In a dredger, a rotary snail-shell shaped digger having a single inlet opening in combination with a rotary pipe to which said digger is rigidly secured.
- 60 5. In a dredger, a submerged or partially submerged pipe, and a rotary snail-shell shaped digger at the extremity of said pipe, said digger having a single cutting edge and a single inlet opening in its periphery.
6. In a dredger, a submerged or partially submerged rotary pipe having at its extremity a snail-shaped rotary digger.
7. In a dredger, a submerged or partially submerged rotary pipe having at its extremity a snail-shaped rotary

digger, said digger having a single projecting cutting edge, 70 and a single inlet opening.

8. In a dredger, a substantially T shaped hydraulic connection, means for receiving spoil through the stem of the T, and a discharge passage for such spoil in one arm of the T.

9. In a dredger, a substantially hinged T-shaped hydraulic connection, means for receiving spoil through the stem of the T, and a discharge passage for such spoil in one arm of the T.

10. In a dredger, a substantially T shaped hydraulic connection, a rotary digger at the extremity of the stem thereof, and a discharge passage through one arm of the T.

11. In a dredger a substantially T-shaped hydraulic connection comprising a rotary stem, arms connected thereto and hinged so as to permit the vertical adjustment 85 of the stem, and a rotary digger rigidly secured to the extremity of said rotary stem.

12. In a dredger, a substantially T-shaped hydraulic connection, the stem wherof has means for receiving spoil, a discharge passage in one arm of the T for the discharge 90 of said spoil and a hydraulic giant in the other arm of the T.

13. In a dredger, a substantially T-shaped hinged hydraulic connection, the stem whereof has means for receiving spoil, a discharge passage in one arm of the T for the discharge 95 of said spoil and a hydraulic giant in the other arm of the T.

14. In a dredger, a substantially T-shaped hydraulic connection comprising a rotary stem, and two hinged arms connected thereto, a rotary digger at the extremity of said 100 rotary stem, and a hydraulic giant in one arm of the T, whereby material excavated is drawn through said rotary stem and is forced through the other arm of the T.

15. In a dredger a substantially T-shaped hydraulic connection having hinge or trunnion bearings for its arms, a 105 gear loose upon one of said arms, driving and transmitting gears in engagement with said loose gear, power connections to the driving gear, a stem for the T adapted to rotate, and means operated by the transmitting gear for rotating said stem; the construction and arrangement being 110 such that the whole T connection can swing upon its hinge or trunnion bearings without deranging or affecting the operation of said gearing.

16. In a dredger means for separating the boulders and large matter from the finer matter and for discharging the 115 boulders by gravity to the bottom of the water hole, a settling sump at the stern of the dredger and below the level of said discharge, means for supplying tailings to said sump, and a chain of buckets or other suitable means for elevating tailings from said sump above said discharge; 120 whereby said tailings are deposited in the water hole above the boulders.

17. In a dredger having means for separating coarse from fine material a settling sump adapted to receive the fine tailings and a chain of buckets, or other suitable 125 means for elevating said tailings from the sump and discharging them from a higher elevation than that at which the coarse waste material is discharged.

18. In a dredger in which material is drawn and forced through and beyond an intake pipe by the action of a hydraulic giant, means for freeing the intake pipe comprising a valve located beyond the giant and adapted to close the discharge passage; whereby the stream from the giant is forced backwardly through the intake pipe.

19. In a dredger, a rotary excavator, a substantially T-shaped hydraulic connection whose hollow stem carries said excavator, a hydraulic giant forming a trunnion bearing for one arm of the T, and a discharge pipe forming a trunnion bearing for the other arm of the T, whereby the whole T-shaped connection can swing upon said bearings 135 without affecting the action of the said giant or the discharge of material through the other arm of the T and said discharge pipe.

In testimony whereof I have affixed my signature, in presence of two witnesses, this 24th day of January 1906. 145
